CLAIMUSPC **D6/310**

I claim the ornamental design for an easel formed from a blank, as shown and described.

(58) **Field of Classification Search****DESCRIPTION**

USPC D6/300–314; D9/433
 CPC ... A47B 23/042; A47B 23/043; A47B 23/044;
 A47B 220/0019; A47G 1/141

See application file for complete search history.

FIG. 1 is a front perspective view of the claimed design after its assembly.

(56) **References Cited**

FIG. 2 is a front elevation view thereof.

U.S. PATENT DOCUMENTS

FIG. 3 is a rear elevation view thereof.

FIG. 5 is a right-side elevation view thereof.

FIG. 6 is a top plan view thereof.

FIG. 7 is a bottom plan view thereof; and,

FIG. 8 is a plan view of a blank of the claimed design before its assembly.

The invention pertains to an ornamental design for an easel formed from a blank. The solid lines represent the bounds of the claimed design, whereas those features shown in broken lines (e.g., bend lines shown in FIG. 8 and a fluted corrugated sheet sandwiched between two face sheets in FIGS. 1-7) form no part of the claimed design.
